UNITED STATES PATENT OFFICE.

HENRY L. CHARLES, OF KENT, WASHINGTON.

SMELTING FURNACE.

Application filed July 30, 1923. Serial No. 654,618.

To all whom it may concern:

Be it known that I, HENRY L. CHARLES, a citizen of the United States, residing at Kent, in the county of King and State of Washington, have invented new and useful Improvements in Smelting Furnaces, of which the following is a specification.

This invention relates to improvements in smelting furnaces of the open hearth reverberatory type and to an improved method of feeding and smelting ore in such furnaces.

The main objects of the invention are to utilize heat which heretofore has been wasted in smelting furnaces, to lengthen the life of the arch by this use of the heretofore wasted heat, to increase the smelting capacity and to increase the efficiency of smelting furnaces.

20 The heat in zones of a smelting furnace located close to the arch is wasted in the ordinary smelting operations, especially in the zones close to the burner. The intense heat provided by the use of the powdered fuel and oil tends to burn out the arch at said points. By providing for smelting within these zones wherein the heat ordinarily is wasted and is destructive to the arch, the arch will not burn out as readily 25 and heat is not wasted.

Another object of the invention is to provide for the utilization of this heretofore wasted heat without requiring that material changes be made in the construction of an ordinary open hearth furnace or necessitating of the employment of a greater heat than is usually required to carry out the ordinary hearth smelting operation and also in such manner that the ordinary hearth 35 smelting operation will not be interfered with.

One way in which I may carry out the invention is to raise the arch adjacent to the burners and provide a smelting chamber 45 above the hearth into which chamber ore is fed through the arch. The burners will extend in the ordinary manner through an end wall of the furnace which also constitutes a wall of the chamber but flames 50 from the burners are directed to portions of the hearth on which the ordinary hearth smelting operations are to be carried out through pipes or conduits. These pipes or conduits extend from the end wall across 55 and through the chamber. Preferably the pipes or conduits are raised above the floor

of the hearth so that smelting zones will be provided around the pipes or conduits. With the chamber filled with ore the ordinary open hearth smelting operation may be carried out and at the same time the ore in the chamber will be smelted. The melted ore will run out of the chamber onto the portions of the hearth where the ordinary hearth operations are carried out. The ore 60 above the pipes or conduits will semi-fuse before the pipes or conduits burn out and the bulk of the ore above this point will be supported before the semi-fused ore gives away. When the body of the ore is melted 65 in the chamber and the walls and arch are being exposed to the heat, a new pipe or conduit is put in place and the chamber is refilled with ore so that the smelting operation may be repeated.

70 Referring to the drawings:

Fig. 1 represents a fragmentary longitudinal sectional view of an open hearth reverberatory furnace which is constructed in accordance with the present invention.

Fig. 2 represents a sectional view taken on the line 2-2 of Fig. 1.

The embodiment of the invention shown in the accompanying drawing takes into consideration the forming of a chamber 85 generally designated A at the burner end of a reverberatory furnace, which latter comprises the usual hearth 1, arch 2 and end walls 3 of which but one is shown. The chamber is provided by raising or building 90 up the portion 4 of the arch over that part of the hearth located adjacent to the burners 5, which burners extend through the wall 3 and slightly into the furnace as is customary in the art.

95 Ordinarily the ore to be smelted is supported by the hearth and the space close to the arch especially adjacent to the burner, is not utilized in the smelting operation. By the formation of the chamber as shown, utilization of this space and the heretofore wasted heat is provided for and the arch is also prevented from burning out as readily as heretofore. In raising the arch 4 there is provided a wall 6 which defines an 100 opening 7 at the lower end through which opening the melted ore from the chamber runs onto the portions of the hearth on which the ordinary smelting operations are carried out. The burners extend into passages 105 preferably provided by open pipes or conduits 8 which extend across and

through the chamber and are preferably spaced above the hearth with their forward ends terminating beyond the roof proper. The heat given off around the conduit will be sufficient to smelt ore within the chamber.

The ore is fed into the chamber by a series of hoppers 9 and 10 which communicate with openings 10' formed through the section 4 of the arch. Connected with openings 10' for the hoppers 10 are feed pipes 11 which extend downwardly into the chamber to points near the hearth. The hoppers 9 provide for the general feeding of ore into the chamber, whereas the hoppers 10 by means of the pipes 11 will cause the ore to be conducted or fed to the lower portions of the chamber. The advantage of this method of feeding is that the ore surrounding the burner conduit 8 will melt first and by feeding ore to be melted into these zones a more efficacious smelting operation may be carried out.

It will be seen that the invention comprises the directing of smelting flames from the burner past a pile or quantity of ore located adjacent the path of the flames and subject to being melted by the heat of the flames. The flames are directed beyond this ore over the portions of the hearth on which the ordinary smelting operations are carried out. The flames may be directed through the ore as shown in the drawings. The pipes or conduits 8 conduct the flames past the ore and temporarily prevent the flames from coming into contact with the ore because when the conduits melt the flames will then make such contact. In this way the utilization of the heat above and also around the path of the flames and close to the arch is provided for and the smelting of ore may be carried out in zones of the furnace which heretofore were not employed to contain ore to be smelted.

It will thus be seen that the flames are prevented from coming into contact with the ore in the chamber only while the conduits or pipes through which the flame passes remain intact and as soon as these pipes or conduits melt, the flames will come in contact with the ore and melt the ore which has not been melted during the time that the flames are directed through the pipe. When the body of ore in the chamber has been melted and the walls of the chamber and arch are exposed to the heat, new pipes or conduits are put in place and the chambers again filled with ore in order that the smelting operation may be repeated. Thus it will be seen that the pipes or conduits 8 prevent contact of the flames with the ore in the chamber at the time of the smelting operation and provide for semi-fusing of the ore around the pipes so as to form a path for the flames when the

pipes or conduits melt away. It is to be understood that iron as well as copper ore may be smelted with the furnace of this invention, since the invention is capable of being carried out in open hearth iron furnaces as well as reverberatory copper furnaces. When the ore around the conduits or pipes 8 becomes semi-fused, the semi-fused portions will support the body of the ore above the flames and fresh ore may be supplied from time to time, particularly at the sides of the chamber where it will be needed soon after the smelting operation begins and when the conduits or pipes 8 are melted away.

While I have shown that the invention may be carried out by raising a portion of the arch near the burner and forming a chamber into which ore is fed through the arch and by directing flames past this body of ore through conduits or pipes, I may however, provide other arrangements and constructions for carrying out the invention without departing from the spirit or scope of the invention as defined by the appended claims.

The vertical pipes 11 may be used to direct fuel, either powdered coal or gas into the chamber so as to intensify the heat. The vertical pipes can be arranged to discharge the fuel into the conduits 8.

I claim:

1. The method of smelting ore in a reverberatory furnace which consists in directing a smelting flame from the burner through a passage in a quantity of ore located in the furnace.

2. The method of smelting ore in a reverberatory furnace which consists in directing a smelting flame from the burner through a passage in a quantity of ore located in the furnace and smelting other ore along the hearth beyond said ore through the agency of said flame.

3. The method of smelting ore in a reverberatory furnace which consists in directing a smelting flame from the burner through a quantity of ore located in the furnace and smelting other ore along the hearth beyond said ore through the agency of said flame without causing contact of the flame with said quantity of ore.

4. The method of smelting ore in a reverberatory furnace which consists in causing a smelting flame to be directed through a quantity of ore disposed in the furnace without causing contact of the flame with the ore.

5. The method of smelting ore in a reverberatory furnace which consists in causing a smelting flame to be directed past a quantity of ore disposed above the path of flame without contact of the flame with the ore.

6. The method of smelting ore in a re-

- verberatory furnace which consists in directing smelting flame over the hearth of the furnace, feeding smelting ore into zones of smelting heat, adjacent to the burner and preventing contact of the flame with said ore thus fed adjacent to the burner.
7. A reverberatory furnace embodying in its construction a hearth, a burner for directing smelting flames over the hearth, an arch over the hearth and having a portion thereof located adjacent to the burner raised with respect to the remaining portion and providing a chamber, said arch having ore feed openings in the raised portion and means for conducting heating flames from the burner through said chamber and to the hearth beyond said chamber.
8. In a reverberatory furnace embodying in its construction a hearth, a burner for directing flames over said hearth, an arch extending over the hearth and having a portion thereof adjacent the burner elevated with respect to the remaining portion, upright walls defining with said elevated portion of the arch and the hearth a chamber located adjacent the burner, one of said walls having an opening therethrough through which melted ore from the chamber will pass onto the hearth and a flame conduit extending from the burner through said chamber and directing flames onto the hearth beyond the chamber, said raised portion of the arch having openings through which ore may be fed to the smelting chamber.
9. A reverberatory smelting furnace embodying in its construction a hearth, a burner for directing flames over the hearth, an arch over the hearth provided with means for feeding smelting ore into the furnace adjacent to the burner and means for directing flames through ore fed into the furnace at points adjacent the burner and over portions of the hearth located beyond the ore thus fed adjacent to the burner.
10. A reverberatory smelting furnace comprising in its construction a hearth, a burner for directing flames over the hearth, an arch over the hearth provided with means for feeding smelting ore into the furnace adjacent to the burner and means for directing flames through ore fed into the furnace at points adjacent the burner and over portions of the hearth located beyond the ore thus fed adjacent to the burner without causing contact of the flames with the ore located close to the burner.
11. The method of smelting ore in a furnace which consists in causing a smelting flame to be directed past a quantity of ore disposed in the furnace and for a part of the time during the smelting operation, without causing contact of the flame with the ore, and for the remainder of the time of the smelting operation by causing contact of the flame with said ore.
12. The method of smelting ore in a furnace which consists in providing a passage through a quantity of ore, then directing a smelting flame through the passage in said ore.

HENRY L. CHARLES.
